UNITED STATES PATENT OFFICE.

NEWTON G. VOSLER, OF MINNEAPOLIS, MINNESOTA.

RAILWAY-CAR.

1,036,038.

Specification of Letters Patent. Patented Aug. 20, 1912.

Application filed March 14, 1911. Serial No. 614,469.

To all whom it may concern:

Be it known that I, NEWTON G. VOSLER, of Minneapolis, Hennepin county, Minnesota, have invented certain new and useful 5 Improvements in Railway-Cars, of which the following is a specification.

My invention relates to a combination sleeping and parlor car and the primary object of the invention is to provide a car having roomy, accessible berths which, during 10 the day, can be easily made up into comfortable seats and lounges.

A further object is to provide a car in which each berth when made up will be cut off or screened from the other berths so that 15 absolute privacy is insured.

A further object is to provide a car having upper berths which are readily accessible without the use of steps or ladders.

Other objects of the invention will appear 20 from the following detailed description.

The invention consists generally in various constructions and combinations, all as 25 hereinafter described and particularly pointed out in the claims.

In the accompanying drawings forming part of this specification, Figure 1 is a plan view of a combined chair and sleeping car embodying my invention, Fig. 2 is a side 30 elevation of the same, Fig. 3 is a detail perspective view illustrating the berths made up for use as seats or lounges during the day, Fig. 4 is a sectional view showing the berths made up for sleeping purposes, Figs. 35 5 and 6 are detail views of the hinged or pivoted back of the seat which, when the berth is made up, forms the floor of the upper berth, Fig. 7 is a detail view illustrating the arrangement of the chairs and 40 the manner of separating one chair from another, Figs. 8 and 9 are detail views of an improved arrangement of the window in the car, Fig. 10 is a detail view showing an improved ventilating device, Fig. 11 is a 45 plan view showing the berths made up, Fig. 12 is a transverse sectional view of the berths, looking toward the aisle of the car.

In the drawing, 2 represents the body of the car, having a side entrance 3 at one end 50 and also preferably provided with a middle entrance 4 on each side leading to a transverse vestibule 5 which divides the car centrally into two rooms or sections. The transverse vestibule allows convenient access 55 to the middle of the car, allowing passengers to enter or leave the car conveniently

from seats or berths near the middle of it, and in case of accident the side entrances will be found particularly convenient. This transverse vestibule feature of the car forms the subject-matter of a companion application herewith and I make no claim to the same herein. On each side of the transverse vestibule longitudinal aisles or passage-ways 60 6 and 7 are provided, communicating with 65 the vestibule 5 through door-ways 8. When these doors are closed the vestibule will be entirely cut off from each end of the car and one end of the car may be chartered for 70 private use while the other end may be open to the public. Each end of the car is provided with the usual toilet rooms 9 and 10 and one end of the car is preferably provided with a smoking room 11. The seats in this car which form the berths at night 75 are preferably arranged transversely of the car and, as shown in Fig. 1, are diagonal, or obliquely arranged with respect to the car to permit the use of a berth of greater length than would be ordinarily possible if 80 they were arranged at right angles to the longitudinal axle of the car. This arrangement of the berths also effects a considerable saving in floor space, allowing room for a 85 row of chairs and the aisle, which could hardly be permitted if berths of this length were arranged straight across the car.

The berths consist of ends 12 and a flat seat bed 13 supported by panels 14 and 15 and by the end panel 12, the opposite end of 90 the seat bed fitting snugly against the wall of the car. A back 16, which extends vertically from the seat bed 13, preferably at one side of the longitudinal center thereof, forms the back rest for one side of the seat. This 95 back has a suitable cushion 17 or it may be upholstered in a suitable manner, and a seat cushion 18 is provided to rest upon the seat bed 13. This back rest 16 is stationary. An arm rest 16' is provided that is adapted to 100 swing back against the stationary back rest or it may drop down to a horizontal position, if preferred, when the berths are made up. When the berth is made up, another cushion corresponding to the cushion 18 is 105 placed on the seat bed beside the cushion on the right hand side of the stationary back rest to fill in the gap made when the movable back rest is lifted, and this extra cushion is usually kept under the seat bed during the day, ready for use when the berth is 110 to be made up.

2

A movable back rest 19 is provided for each section, adapted to rest upon the seat plate 13 during the day, when the berth is used as a seat, and provided with loops 20 at their upper edges which are adapted to receive and slide on pins 20' inserted in the wall of the car and the end panel 12. (See Figs. 3, 11, and 12.) The loops and the pin form a sliding connection to allow the back rest to drop down upon the seat bed and when it is raised to a horizontal position it can be moved inwardly so that one edge will overhang the stationary back rest.

A cushion 21 is provided for the back rest 19 which has a flap 22 adapted to cover the joint between the upper edges of the movable and stationary back rests. This movable back rest is composed, preferably, of longitudinal and end rails 23 and 24, pivotally connected and adapted to swing on their pivots from a rectangular form, as shown by full lines in Fig. 6, to the position indicated by dotted lines in Fig. 6. This is to allow the movable back rest to adapt itself for use as a back rest during the day and as the floor of the upper berth at night.

When the movable back is raised it is swung on the pivots 20' to a horizontal position and then pushed inwardly until one edge is flush substantially with the edge of the seat bed, as shown plainly in Figs. 4 and 12. Sockets 25 are provided in the wall of the car and the end panel 12 to receive bolts 25' mounted on the movable back rest. The pivotal connection between the longitudinal and transverse rails of this back rest allows the rest to be readily adapted for its different positions. During the day when it is in use as a back rest it will assume a substantially rectangular form, but when it is swung to a horizontal position to form the bottom of the upper berth the cross bars will swing on their pivots to conform to the diagonal arrangement of the berth, as shown plainly in Fig. 11. I regard this construction of the movable back rest as an important feature of my invention.

A flexible curtain 26 is provided extending from one edge of the back rest 19 to the top of the car and effectually screening the upper berth from the lower one, and a similar curtain or wall 27 is provided between the seat bed 13 on the side contiguous to the cushion 18, also extending to the top of the car and screening the upper berth from the lower berth of the adjoining section, as plainly shown in Fig. 4. Suitable curtains also will be provided, as usual, for screening each section from the aisle of the car. In place of this curtain suitable partitions of any kind may be employed and still be within the scope of my invention. In case wooden partitions are provided to separate the sections from one another, the usual heavy curtains will be hung between each

section and the aisle of the car. This arrangement allows the occupant of the lower berth to dress or undress on the floor of the car with the same privacy as in an ordinary compartment car, and the occupant of the upper berth may stand on the cushion 18 of the seat bed and have convenient access to the upper berth without the use of steps or ladders, and this berth will also be effectually screened from the aisle and will provide the same privacy as a section in a compartment car.

I prefer to provide suitable wash-stands 28 in connection with each lower berth at the side of the car and other toilet conveniences, such as mirrors, and racks of various kinds fastened to or concealed in the wall of the car, may be provided. I have not thought it necessary, however, to illustrate this herein. The curtains 26 and 27 may be mounted on the movable back rest and the seat bed or they may be detachable therefrom and folded up during the day and placed in the space beneath the seat bed with the pillows and other bedding, if preferred.

In Fig. 7 I have shown a form of chair which I prefer to provide in this car, adapted for sitting up, or reclining, as desired, consisting of a seat portion 28 having an adjustable back 29 and a pivoted foot rest 30, each chair being separated from the adjoining one by a partition 31. As shown in Fig. 7, the chair may be adjusted to form a bed lounge at night, being separated from the car aisle by a suitable curtain depending between the chair or section and the aisle. I also prefer to provide an improved form of window in the wall of the car, consisting of a sash 32 pivoted at 33 and adapted to swing outwardly to an open position and contacting with stops 34 and 35 when closed. The arrangement of this sash will serve to deflect dust and cinders and prevent them from entering the car. I also provide a ventilating device in the top of the car, consisting of a fan 36 geared to a shaft 37, which may be power driven or operated by means of propellers 38 mounted in the roof of the car. The fan 36 is preferably arranged in a chamber 39 having trunks 40 which communicate through gratings 41 with the interior of the car. This chair device, with the window and the ventilator, forms the subject matter of separate applications and are not claimed in detail herein.

I claim as my invention:—

1. A sleeping car berth comprising a seat bed having a stationary back rest mounted between the longitudinal edges of said seat bed and a movable back rest, said movable back rest being adapted to swing to a horizontal position to form the floor of the upper berth, said seat bed and stationary back rest being arranged diagonally in the car

- and extending transversely thereof, and said movable back rest being composed of pivotally connected side and end rails to allow it to accommodate itself to the angle of the stationary back rest and the side wall of the car, means supporting said movable back rest in its horizontal position, and partitions separating the upper and lower berths of a section from the adjoining sections. 5
2. A sleeping car having a berth comprising a seat bed disposed transversely of the car and diagonally therein, a stationary back rest mounted thereon, an end panel, a movable back rest having pivotal connections at its upper edge with the car wall and with said panel and composed of side and end rails capable of oscillation on their pivots to adapt said movable back rest to the angle of said stationary back rest with respect to the car wall, said movable back rest, when raised, forming the upper berth, and the seat bed beneath said back rest, when raised, forming the lower berth, and means separating the upper and lower berths from the adjoining sections. 10
3. A sleeping car berth comprising a seat bed and a stationary back rest mounted thereon near the middle portion of said seat bed, a movable back rest normally resting upon said seat bed and adapted to be moved to a horizontal position with one longitudinal edge resting on said stationary back rest, means supporting the opposite longitudinal edge of said movable back rest to form the bottom of the upper berth, said seat bed on one side of said stationary back rest forming the lower berth and the opposite side of said seat bed forming a raised support for convenient access to said upper berth, and suitable curtains separating said upper and lower berths. 15
4. The combination, with a car, of a combined seat and berth disposed transversely of the car and diagonally with respect to the side walls thereof and comprising a flat seat bed, an end panel therefor, a stationary back rest mounted on said seat bed, a movable back rest pivotally connected at its ends with said end panel and with the wall of the car and adapted to swing to a horizontal position with one edge overhanging the upper edge of said stationary back rest, means supporting the other edge of said movable back rest, said movable back rest forming the bottom or floor of the upper berth, said seat bed on one side of said stationary back rest forming a step for convenient access to said upper berth, said seat bed on the other side of said back rest forming the floor of the lower berth, and flexible partitions or curtains separating said berths from the adjoining sections. 20
5. The combination, with a car, of a combined seat and berth disposed transversely of the car and diagonally arranged with respect to the walls of the car and comprising a stationary seat bed, back rests provided near the middle of said seat bed, one of said back rests being movable and composed of pivotally connected sections adapted to assume rhomboidal form and swing to a horizontal position parallel substantially with said seat bed and above the same to form the bottom of the upper berth, the seat bed beneath said movable back section when raised forming the lower berth, and suitable curtains for said berths, the diagonal arrangement of said berths in the car permitting seats and berths of greater length. 25
6. A railway car having transversely arranged berths composed of seat beds and stationary back rests centrally arranged with respect to said beds, movable back rests provided on one side of each stationary back rest and adapted to swing upwardly to a horizontal position, pivot pins provided at the ends of said movable back rest, loops mounted on said back rests to receive said pivot pins and whereon said movable back rests are slideable horizontally, means supporting the outer edge of said movable back rests, said movable back rests forming the bottoms of the upper berths and said seat beds on one side of said stationary back rests forming the bottoms of the lower berths. 30
7. A sleeping car berth comprising a seat bed, a stationary back rest thereon, a movable back rest having a sliding pivotal connection at its upper edge and adapted to swing upwardly to a horizontal position to form the bottom of the upper berth, the seat bed beneath said movable back rest forming the lower berth, and suitable partitions separating the berths of one section from those of the adjoining sections. 35
8. A sleeping car berth comprising a transverse seat bed and a stationary back rest mounted thereon, a movable back rest adapted to swing to a horizontal position to form the bottom of the upper berth, the seat bed on one side of said stationary back rest forming the bottom of the lower berth and the seat bed on the opposite side of said stationary back rest forming a raised floor or support when the berth is made up to permit convenient access to said upper berth, and means screening the upper from the lower berth. 40
9. The combination, with a car, of a seat bed disposed transversely thereof and having a stationary back rest intermediate to its longitudinal edges, a movable back rest having one edge adapted to rest on said seat bed and capable of swinging to a horizontal position and resting upon said stationary back rest to form the floor of the upper berth, the seat bed beneath said movable back rest when raised forming the lower berth, and said seat bed on the opposite side of said 45

stationary back rest from said lower berth forming a floor or standing room for the occupant of the upper berth, and means screening one berth from the other.

5 10. The combination, with a car, of a seat bed having a back rest intermediate to its longitudinal edges, one side of said seat bed forming the bottom of the lower berth, the other side of said seat bed forming standing 10 room for access to the upper berth, and means overhanging the said one side of said seat bed and forming the floor or bottom of the upper berth.

11. A sleeping car having a berth comprising a seat bed and a stationary back rest mounted thereon, a movable back rest disposed on one side of said stationary back rest and adapted to swing up to a horizontal position to form the bottom of the upper 15 berth, the seat bed on one side of said stationary back rest forming the bottom of the lower berth and the seat bed on the opposite side of said back rest being unobstructed 20 and forming a raised floor or standing room 25 when the berth is made up to allow convenient access to the upper berth.

12. A sleeping car having a berth comprising a seat bed, a stationary back rest extending lengthwise of said seat bed and near 30 the middle portion thereof, a movable back rest, the inner longitudinal edge of said movable back rest being pivotally and slidably supported, said movable back rest being capable of swinging upwardly to a substantially 35 horizontal position and having a sliding movement on its pivots transversely of the berth above said stationary back rest, said movable back rest forming, when raised, the floor of the upper berth, and 40 means supporting said back rest in its raised, horizontal position.

13. In a sleeping car, a berth comprising

a transverse, stationary back rest and a seat bed on each side of said back rest, a movable back rest provided on one side of said 45 stationary back rest and having a sliding, pivotal connection at its upper edge and adapted to swing upwardly to a substantially horizontal position with its inner edge overhanging the upper edge of said stationary back rest, said movable back rest forming the floor of the upper berth, the seat bed on one side of said stationary back rest forming the lower berth, and the seat bed on the other side of said stationary back rest 50 forming a standing room or raised floor for convenient access to the upper berth, and partitions separating said upper and lower berths from the adjoining sections.

14. A sleeping car having a berth comprising a transverse, stationary back rest and a seat bed on each side thereof, and end panels for said seat beds, said panels having movable sections, a movable back rest adapted to swing upwardly to a substantially horizontal position, means supporting said movable back rest in its horizontal position, the seat bed beneath said movable back rest forming the floor of the lower berth and said movable back rest forming when raised to a 60 horizontal position, the ceiling of the lower berth, and the floor of the upper berth, the seat bed on the other side of said stationary back rest forming a raised floor or standing room for access to said upper berth and said 65 movable section allowing convenient access to said standing room, and suitable curtains for said berths.

In witness whereof, I have hereunto set my hand this 8th day of March 1911.

NEWTON G. VOSLER.
